UNITED STATES PATENT OFFICE

FRANK J. WERNER, OF PORTAGE TOWNSHIP, PORTER COUNTY, INDIANA

BURNER STRUCTURE

Application filed May 31, 1934. Serial No. 717,034.

My invention, as to one phase thereof, relates to improvements in liquid fuel burners; as to another phase thereof, to improvements in gas burners; as to another phase 5 thereof to powdered fuel burners; and as to another phase thereof, to a burner adapted for use with either liquid, gaseous or powdered fuel supplied simultaneously or interchangeably.

One of my objects is to provide improvements in liquid fuel burners to the end that a wide variety of liquid fuels may be employed as desired, supplied at any pressure within a wide range thereof from a relative- 10 ly low pressure, such as that generated by gravity, to a relatively high pressure of say approximately 200 pounds per square inch; and to provide a construction whereby the liquid fuel will be practically perfectly 15 atomized, thereby insuring complete combustion of the fuel with the attendant advantages one of which is fuel economy.

Another object is to provide a novel construction of gas burner for use with a wide 25 variety of gases, such, for example, as natural gas, by-product-coke-oven gas, or gas-producer gas, supplied under any pressure; another object is to provide a gas burner which shall be adapted, through manipula- 30 tive adjustment, under variations in pressure of the gas supplied to the burner, to produce substantially complete combustion of the gas, with the attendant advantages one of which is economy of gas consumption.

Another object is to provide a novel construction of powdered fuel burner which 35 will be highly efficient in its operation, producing complete combustion of the fuel.

Another object is to provide, either a 40 liquid fuel, powdered fuel or gas burner, for the producing of various shapes of flames, as desired, ranging from a comparatively thin pencil-like flame to a very wide flaring flame, to perform the particular work 45 required; and another object is to provide for economizing in the steam consumption where steam is supplied to the burner.

Another object is to provide a burner 50 which is adapted to be operated with either gaseous, liquid or powdered fuel simultane-

ously, or with the different kinds of fuels interchangeably, and with the maximum economy of fuel and without appreciable loss of time in changing from one to another kind of fuel.

Referring to the accompanying drawings:

Figure 1 is a view in vertical sectional elevation of the fuel-inlet-port-equipped wall of a furnace, showing it as equipped with a burner-structure embodying my invention 55 and shown as coupled with piping provided in a suitable arrangement, especially where a battery of the burner-structures are employed, certain of the parts referred to being broken away and others shown in section. Figure 2 is a view in front elevation of the burner-structure and the piping and connections shown in Fig. 1. Figure 3 is an enlarged, broken, sectional view taken at the lines 3 on Figs. 2 and 4 and viewed in the direction of the respective arrows. Figure 4 is a section taken at the line 4 on Fig. 3 and viewed in the direction of the arrows. Figure 5 is a view in vertical longitudinal sectional elevation of the front end of the burner-structure, showing the parts thereof in a position occupied by them when the burner is operating with liquid fuel. Figure 6 is an enlarged section taken at the line 6—6 on Fig. 5 and viewed in the direction of the arrows. Figure 7 is an enlarged section taken at the line 7—7 on Fig. 5 and viewed in the direction of the arrows. Figure 8 is an enlarged section taken at the line 8—8 on Fig. 5 and viewed in the direction of the arrows. Figure 9 is an enlarged section taken at the line 9—9 on Fig. 5 and viewed in the direction of the arrows. Figure 10 is a plan sectional view of the burner of the preceding figures, showing the parts thereof in the position shown in Figs. 5 to 9 inclusive, the section being taken at the line 10 on Fig. 1 and viewed in the direction of the arrow. Figure 11 is a view like Fig. 10 of the construction therein shown, showing the parts in a position which they occupy when the burner is operating with either gaseous or powdered fuel, certain of the parts being shown in elevation. Figure 12 is an enlarged sectional view of the discharge end of the burner with 100

the parts thereof shown in the position represented in Fig. 5, with an additional sectional showing to illustrate details of this part of the burner. Figure 13 is a similar view of a 5 certain portion of the structure shown in Fig. 12, with certain parts broken away and other parts shown in disassembled, but related, position. Figure 14 is a section taken at the line 14 on Fig. 13 and viewed in the 10 direction of the arrow. Figure 15 is a rear end view of the structure shown at the left hand side of Fig. 10. Figure 16 is a plan section taken at the line 16—16 on Fig. 4 and viewed in the direction of the arrows, illustrating 15 a shutter-valve for the powdered-fuel-hopper, the valve being closed. Figure 17 is a similar, broken, view of the structure shown in Fig. 16, showing the valve in open condition. Figure 18 is a plan view of the rear 20 end of the burner-structure; and Figure 19, a section taken at the line 19 on Fig. 18 and viewed in the direction of the arrow.

I have chosen to illustrate my invention, as to its various phases, in a burner-structure 25 adapted, through the manipulative adjustment afforded, for use with either liquid, gaseous, or powdered fuel, but without the intention, however, of limiting it to its embodiment in a structure suitable for use with 30 all of these kinds of fuel. The particular burner-structure shown comprises an outer, double-walled casing 20 the wall 21 of which circumscribes the wall 22 thereof and is in spaced relation thereto, to form the space 23 through which a cooling medium, as, for example, water, may be circulated to maintain the burner in relatively cool condition, this space being shown as communicating, at the 35 rear end of the burner, with an inlet pipe 24 located in the lower portion of the space 18 and an outlet pipe 25 located in the upper portion of this space. The front end of the casing 20 is shaped, as shown, to form a relatively restricted opening 26 therethrough, 40 and the inner surface of the forward end of the casing, and including the wall of the opening 26, is lined with a body 27 of any suitable refractory material containing an opening 28 therethrough which forms the outlet of the 45 burner.

The inner surface of the inner wall 22 of the casing 20 is shown as provided with a series of bars 29 shown as grouped about the longitudinal axis of the casing and extending 50 parallel with each other lengthwise of the casing and preferably equidistantly spaced apart as shown, these bars extending rearwardly beyond the casing 20, as illustrated.

55 Located within, and longitudinally slid- able in, the wall 22 of the casing 20, is a member 30 shown as of cylindrical form and containing grooves 31 extending lengthwise in its periphery into which the guide bars 29 60 extend, the member 30 containing an open-

ing, represented at 32, which extends entirely lengthwise therethrough, with its wall shaped substantially as in the case of a Venturi tube, the rear end of the member 30 containing a threaded socket, represented at 33, for receiving a tool represented at 34 and shown in the form of a rod, by which the member 30 may be adjusted lengthwise of the casing 20, as desired. 70

The burner-structure also comprises a 75 burner-head, represented generally at 34, located in, and slideable lengthwise of, the casing 20, the external diameter of the head 34 being considerably less than the internal diameter of the inner wall 22 of the casing. 80 The head 34 comprises an inner tubular member 35 open at its opposite ends and containing in its forward end a Venturi tube 36 shown as provided with an external annular flange 37 forming a shoulder 38 at which it 85 extends flatwise against the extreme forward edge of the tube 35, with the peripheral surface of the flange of frusto-conical shape to present the annular beveled surface 39. Surrounding, and screwed upon, the threaded portion 40 of the tube 35, is a ring-shaped member 41 provided with a forwardly-extending sleeve-like portion 42 terminating in a rounded forward extremity 43, apertured as indicated at 44, through which the tube 35 90 extends. The wall of the opening 44 throughout its extent is spaced from, and held concentric with, the outer surface of the tube 35 in any desired manner to form an annular outlet from the chamber 45 defined by the tube 35 and sleeve 42. The sleeve 42 between its ends, is provided with an annular inwardly-extending flange 46 and an annular outwardly-extending flange 47, the flange 46 95 forming the rear wall of the chamber 45 and, with the tube 35, sleeve 42 and the ring 41, forming an annular chamber 48 which communicates with the chamber 45 through an annular series of openings 49 in the flange 46, the ring 41 containing a passage 50 forming an inlet for the chamber 48. Surrounding the sleeve-like member 42 and concentric therewith, is another sleeve-like member 51 of the same general shape as the member 42, with its inner surface spaced, throughout its 100 extent, from the outer surface of the member 42. The member 51 is screwed at its threaded portion 52 upon the ring 41 and its forward end contains an opening 53 into which the tube 35 extends, the wall of this opening is held concentric with the tube 35 and spaced therefrom in any desired manner to provide a narrow annular passage between the tube 35 105 and the member 51 which passage, in the particular construction shown, is of the same cross-sectional area as the passage provided at the opening 44 in the sleeve 42. The provision of the sleeve-like members 42 and 51 and flange 47 causes the device to present an 110 115 120 125 130

annular chamber 54 which surrounds the chamber 45 adjacent the flange 46 and 47, the outlet of the chamber 54, located between the openings 44 and 53, is annular and narrow being disposed in a plane substantially at a right angle to the longitudinal axis of the tube 35 and a uniform width of opening throughout its circumference, the outer peripheral surface of which latter opposes the outlet of the chamber 54, as shown. The flange 47, together with the sleeve-like members 42 and 51 and the ring member 41, afford an annular chamber 55 which communicates with the chamber 54 through a circular series of openings 56 in the flange 47, the ring 41 containing a passage 57 forming an inlet for the chamber 55. The parts just described, certain of which are adjustable relative to each other as hereinafter described, are rigidly held against accidental displacement as by means of a lock-nut 58 screwed upon the rear end of the tube 35 and against the ring member 41.

The burner head also comprises a member 59 which is of general frusto-conical form with its smaller end at the rear of the burner. The member 59 surrounds and is mounted on, a pipe 60 screwed into the rear end of the tube 35, the forward end of the member 59, which is annularly recessed, as represented at 61 and 62, to adapt it to fit over the rear end of the tube 35 and the nut 58, being provided with a forwardly-extending annular flange 63 which fits over upon the ring member 41, a nut 64 screwing upon the threaded portion 65 of the pipe 60 and against the forward end of the member 59 serving as a lock-nut to hold the parts in position. The member 59 contains openings 66 and 67 extending therethrough in which pipes 68 and 69 connected with the ring-member 41 and communicating with the inlets 50 and 57, respectively, extend.

The pipes 60, 68 and 69 extend through the member 30 which latter forms a support for the burner head through the engagement of the pipes 68 and 69 therewith.

The burner apparatus also comprises a disk-like head 70 at the rear end thereof, in which the outer ends of the guide-bars 29 are secured, and sleeve-members 71 and 72 arranged end-to-end and surrounding the bars 29 and interposed between the casing 20 and the disk 70. At intervals the bars 29 are surrounded by rings 73, 74 and 75, the rings 73 and 75 being located within, and tightly fitting, the sleeves 71 and 72, respectively, and the ring 74 being located within, and tightly fitting, both sleeves 71 and 72 at the joint therebetween. To prevent displacement of the rings on the bars 29 the latter are notched at intervals about their outer peripheries, as represented at 76 and the rings are provided with lugs 77 about their inner peripheries 65 which extend into the notches 76. A pipe 78,

open at both ends and secured at its rear end to the disk 70 and of a diameter considerably less than the internal diameter of the sleeves 71 and 72 through which it extends, surrounds the pipes 60, 68 and 69 and extends 70 part way into the casing 20 as shown (Fig. 10), the pipe 78 opening into a pair of blast-pipes 79 and 80. The sleeve 72, which is stationary, forms one element of a powdered-fuel feed-device and to this end its circular 75 wall is apertured, these apertures being shown as in the form of parallel slots 81 obliquely disposed to the axis of the sleeve 72 (Fig. 11). Another element of this feed device is in the form of a sleeve 82 located 80 within, and slidable in, the sleeve 72, with apertures 83 therein of the same form as, and registering with, the apertures 81 in the sleeve 72. The sleeve 82 is slidable as stated 85 to regulate the flow of powdered fuel inwardly into the sleeve 82 and is provided with a shifting element in the form of a bar 84 located inside the sleeve 72 and 82, with one end attached to the sleeve 82 as by the yoke 85 and its other, outer, end accessible, 90 for operation, at the rear end of the burner-structure.

Surrounding, and cooperating with, the sleeve 72 and 82 is a sleeve 86 rotatably mounted on roller bearings 87, the sleeve 86 95 containing apertures 88 in its periphery of the same form as, and in certain positions of said sleeve 86 registering with, the apertures 81 in the sleeve 82 and operating, in its rotation, to control the flow of powdered fuel 100 inwardly through the apertures 83 and 81.

The ends of the sleeve 72 extend through openings 89 in a casing 90 which is shown as bolted at 91 to the floor, this casing, which aids in supporting the burner-structure 105 described, containing an opening 92 in its top portion of less cross-sectional area than the area of said top-portion whereby this opening is flanked by the flange-portions 93. Extending downwardly into the casing 90 through its opening 92 is a hopper-structure 94 which rests at outwardly-extending flanges 95 thereon upon the flanges 93. The hopper-structure 94 contains an opening 94^a therethrough at which it surrounds the ends 110 of the rotatable sleeve 86, and its lower end is of general circular shape, as represented at 96, and concentric with the sleeve 86, but spaced therefrom as shown. Opposed sidewall portions of the hopper-structure 115 through which the sleeve 86 extends, are provided with rings 97 in the interior thereof, which are of angular shape in cross-section, as shown, and surround the sleeve 86 and form a constriction of that portion of the 120 hopper-structure immediately adjacent the apertured portion of the sleeve 86.

The drive-means for the sleeve 86 comprise gears 98 secured to the ends of this sleeve 125 and located within the spaces 99 provided 130

between the hopper-structure and the casing 90, these gears meshing with pinions 100 carried by a shaft 101 journaled in the casing 90 and shown as driven by a motor 102 through the medium of a worm wheel 103 and worm 104 on the shaft 101 and the driven shaft of the motor 102, respectively.

The hopper-structure is provided with means to control the flow of powdered fuel therein to the feed-device described, these means as shown comprising a pair of shutter-plates 105 and 106 extending crosswise of the hopper at opposite sides thereof and slidably confined in guide-ways 107 and 108. The plates 105 and 106 at their outer edges are connected with the inner ends of rods 109 and 110, respectively, the outer ends of which carry parallel, spaced-apart, bars 111 and 112, respectively, located exterior of the hopper-structure. The rods 109 and 110 extend through the respective bars 111 and 112 with spacer-sleeves 113 and 114 located between the rods of the pairs thereof and surrounding these rods, nuts 115 and 116 screwed on the rods holding these several parts in assembled relation. Extending upwardly into the spaces between the bars 111 and 112 are levers 117 and 118 the upper ends of which are of general circular shape, as shown, these levers being pivoted at their lower ends, as represented at 119 and 120 on arms 121 and 122 extending laterally outward from the casing 90. The levers 117 and 118 are pivotally connected, at 123 and 124, with the outer ends of rack-bars 125 and 126 which extend at opposite sides of, and in mesh with, a gear 127 fixed on a shaft 128 journaled in the hopper-structure and provided with a hand-wheel 129, the bars 125 and 126 at their lower and upper edges, respectively, opposing curved guide surfaces 130 and 131 formed in hollow members 132 secured to the hopper-structure and through which the shaft 128 extends.

The burner-structure is shown as installed in a furnace and forms one of a battery of similar burner-structures, the discharge-end portion of the burner-structure shown being located in an opening 133 in the wall of the furnace, which, by way of example, is an openhearth furnace. In the particular apparatus shown provision is made for supplying cooling water to the casing 20, and gas, air, steam and oil, as desired and under the control of the operator, to the burner, the arrangement shown being especially adapted for the supplying of the fluids referred to, to any one or more of a battery of burner-structures. Accordingly there is provided a series of headers for each fluid, which headers in practice would extend crosswise of the battery of burner-structures, so that the desired connections may be made between each of these headers and each of the burner-structures. The header for the gas supply is

represented at 134 and connects by a valved branch pipe 135 formed with a flexible section 136, with the pipe 60 intermediate the ends of the latter, the outer end of this pipe being open to the atmosphere, with the opening to the atmosphere controlled by a valve 137. Two headers for the compressed air supply are shown, one being represented at 138 and the other at 139. The header 138 is shown as provided with a branch pipe 140 valved at 141 and connected, by a flexible pipe 142, with one branch 143 of a coupling 144 connected with the pipe 68, the other branch portion being represented at 145. The header for the steam supply is represented at 146 and is shown as provided with a branch pipe 147 having a valve 148 and connected, by a flexible pipe 149, with the branch portion 145 of the coupling 144. The header 139 connects with a branch pipe 150, valved at 151 and into which the pipes 79 and 80 open. The header for the oil supply is represented at 152 and is provided with a branch pipe 153 valved at 154 and communicating with a flexible pipe section 155 which connects with the pipe 69. The headers for the water-supply and water-discharge are represented at 156 and 157, respectively, the header 156 having a valved branch pipe 158 which communicates with the pipe 24 and the header 157 having a branch pipe 159 which communicates with the pipe 25.

Referring to the use of the burner-structure with liquid fuel, the fuel is introduced into the burner through the pipe 69 from which it flows into chamber 55 and thence substantially uniformly through the openings 56 in the flange 47, into the chamber 54. Simultaneously with the flow of liquid fuel as stated, air or dry steam, as desired, dry steam being preferred as it serves to heat the liquid fuel, is caused to flow through pipe 68 into chamber 48 and thence through the openings 49, into chamber 45 from which the air or steam, as the case may be, discharges through the passage 44, thus flowing in a circular stream along the outer surface of the tube 35 and crosswise of the annular stream of liquid fuel supplied through the outlet of the chamber 54, the effect of directing the liquid fuel against the tube 35 and causing it to be subjected to air or steam discharging through the passage 44 being to thoroughly atomize the liquid fuel, the mixture thus produced discharging through the passage 53 and thence across the tapered surface 39 of the tube 36. The air or steam thus supplied is not sufficient, in the particular construction shown, to support final combustion of the fuel, and thus supplemental air is required to be furnished to the mixture to produce complete, or substantially complete, combustion in the furnace. Where the furnace is of such construction, as in the case of an open-hearth furnace, that the

requisite amount of supplemental air is supplied to the fuel through the furnace structure, as distinguished from through the burner, to produce complete combustion, no supplemental air need be supplied through the burner. Where, however, supplemental air is required to be supplied through the burner, it may be supplied, by way of example, through pipe 60 by closing the valve 5 in pipe 135 and opening valve 137, or through casing 20 by adjusting the member 30 along the casing in a direction to the right in Fig. 12 to a position in which the desired clearance between the member 30 and the member 59 is presented, it being understood that the effect of the atomized fuel mixture discharging through the passage 53 over the bevel surface 39 is to produce an injector action which operates to suck air into the burner through the casing 20 or pipe 60 or both, as the case may be.

The chamber 45 has been described as an air or steam chamber, and the chamber 54 as a liquid-fuel chamber, but, if desired, such condition may be reversed in which case the liquid fuel would discharge through the passage 44 into the air or steam discharging from chamber 54. The results from such reversal would not be as good, however, as a more perfect atomization of the fuel may be effected by discharging the air or steam against the liquid fuel, as hereinabove described.

To use the burner-structure for burning gaseous fuel, both the member 30 and the burner-head are shifted in the casing 20 to the right from the position shown in Fig. 12, to afford between the burner-head and the discharge end of the casing 20 a relatively large mixing chamber and open this chamber to the atmosphere; the supply of liquid fuel to the burner is shut off, and the pipe 60 opened to the gas-header 134, the valve 137 being closed.

Where the gas to be burned is supplied under relatively low pressure, say below one pound pressure, it is desirable that air or steam be supplied to the burner through pipe 68, and if the furnace-structure is not of a character whereby supplemental air for final combustion is supplied otherwise than through the burner, the requisite supplemental air is supplied from the atmosphere through the casing 20 by adjusting the member 30 lengthwise therein to the desired position. The air or steam supplied through the pipe 68, under pressure, as stated, exerts, in its passage across the surface 39, suction in the pipe 60 and also in the space 55 between the burner-head and the casing 20, with the result of pulling gas through the pipe 60 and air through the space referred to, into the mixing chamber referred to, where the gas becomes intimately mixed with 60 the air or steam or both, as the case may be.

Where the gas to be burned is supplied under such pressure that suction thereon is not necessary to cause the desired volume of gas to be supplied to the mixing chamber, the supplying of air or steam through the pipe 68 is unnecessary, the desired volume of air for supporting complete combustion being supplied, if desired, only through the space between the burner-head and the casing by the suction action of the incoming gas.

In the conditioning of the burner for burning gas, the amount of gas required to be delivered to the combustion chamber for accomplishing the work to be done is first determined, and a nozzle 36, having its central opening of such size that for the particular gas pressure to be used the desired volume of gas will be supplied to the mixing chamber, is selected, it being understood that the lower the pressure of the gas the larger the opening necessary in the nozzle 36.

The member 29, in the conditioning of the burner for burning gas, is moved to the desired position for permitting the requisite amount of air to be drawn into the mixing chamber, and the burner-head is adjusted lengthwise of the casing 20 to provide a mixing chamber of the proper size for insuring the proper mixture therein of the gas with the air, for the particular gas pressure employed, it being understood that the higher the gas pressure, the larger the mixing chamber is required to be in order to insure the desired intermixture.

It will be further understood that by providing the burner-head and member 30 adjustable independently of each other and lengthwise of the casing 20, the size of the mixing chamber and the flow of air through the casing may be varied at will, thereby providing for the conditioning of the burner to produce the proper proportions of gas and air or steam, and the proper admixture of these ingredients regardless of the pressure at which the gas is supplied.

The nozzle 36, through its support on the tube 35, and the sleeves 42 and 51 being relatively adjustable lengthwise of the burner, the relative positions of the beveled surface 39 and the sleeves referred to may be varied to vary the shape of the flame produced by the burner, whether used as a liquid-fuel or gas burner. Thus a long and narrow flame, wide and short flame, or flames of forms intermediate those just stated, may be produced as conditions require. Furthermore, by substituting for the tube 36 a similar tube having a smaller or a larger opening therein, a greater or lesser velocity through this tube may be produced, as conditions may require.

In the use of the burner structure with powdered fuel, the burner head and member 30 are retracted as in the case of the use of the structure with gaseous-fuel as above de-

scribed, and as, for example, to the position shown in Fig. 11, the valve 151 and shutter-valve for the hopper are opened, and the motor 102, for operating the fuel-feeding mechanism, started. The action of the fuel-feeding mechanism and the blast through the pipes 79 and 80 which issues from the rear end of the pipe 78 into the casing 20, results in the flow of powdered fuel and air through the member 30 and thence into the mixing chamber in the rear of the burner-head, the mixture issuing from the burner becoming ignited, the blast of air discharging from the pipes 79 and 80 exerting suction action in the space around the pipe 78 which, in turn, exerts suction action on the fuel and the atmosphere, thereby drawing the fuel and air from the atmosphere into the mixing chamber, it being understood that the various parts of the burner-structure would be so adjusted and the air-blast so regulated, as to meet the particular conditions presented.

It will be understood from the foregoing that the member 30 may be conveniently adjusted by means of the rod 34 which is screwed into the opening 33 in this member. The rod 34 also forms a means whereby, upon removing the member 30, the lining portion 27 of the casing 20 may be withdrawn from the latter, the threaded opening 27^a therein being provided to receive the rod 34.

While I have illustrated and described a particular construction embodying my invention, I do not wish to be understood as intending to limit it thereto, as the same may be variously modified and altered without departing from the spirit of my invention, and in this connection it will be understood that I do not intend to limit my invention, as regards the features thereof relating separately to a liquid-fuel burner, a gaseous fuel burner and a powdered-fuel burner, to the combining of any of these features in a burner to adapt it for use with more than one kind of fuel.

What I claim as new, and desire to secure by Letters Patent is:

1. A burner comprising a burner head formed with a tubular member presenting a passage therethrough, means for delivering gas to said passage, means for delivering a combustion-supporting agent to said passage, conduits surrounding said member, one of said conduits being for liquid fuel, means for delivering an atomizing agent to the other of said conduits, means for delivering a combustion-supporting agent to said last-referred-to conduit, the walls of said conduits at their outlet portions being arranged at different points along, and spaced from, said member, and the outlet of the front one of said conduits opening towards said member, whereby the fluid discharging from said first-

referred-to conduit discharges towards the side of said member and into the path of the fluid flowing out of the space between the wall of the rear one of said conduits and said member.

2. A burner comprising a burner head formed with a tubular member presenting a passage therethrough, means for delivering gas to said passage, means for delivering a combustion-supporting agent to said passage, conduits surrounding said member, one of said conduits being for liquid fuel, means for delivering an atomizing agent to the other of said conduits, means for delivering a combustion-supporting agent to said last-referred-to conduit, the walls of said conduits at their outlet portions being arranged at different points along, and spaced from, said member, the front one of said conduits being a liquid fuel conduit with its outlet opening towards said member, whereby the liquid fuel discharges towards the side of said member and into the path of the agent flowing out of the space between the wall of the rear one of said conduits and said member.

3. A burner comprising a burner head formed with a tubular member presenting a passage therethrough, means for delivering gas to said passage, means for delivering a combustion-supporting agent to said passage, conduits surrounding said member, one of said conduits being for liquid fuel, means for delivering an atomizing agent to the other of said conduits, means for delivering a combustion-supporting agent to said last-referred-to conduit, the walls of said conduits at their outlet portions being arranged at different points along, and spaced from, said member, and the outlet of the front one of said conduits opening towards said member, whereby the fluid discharging from said first-referred-to conduit discharges towards the side of said member and into the path of the fluid flowing out of the space between the wall of the rear one of said conduits and said member, and a casing in which said burner head is located, said casing containing an outlet, with the burner head movable in said casing toward and away from said outlet, the space between said outlet and said burner head constituting a mixing chamber.

4. A burner comprising a burner head formed with a tubular member presenting a passage therethrough, means for delivering gas to said passage, means for delivering a combustion-supporting agent to said passage, conduits surrounding said member, one of said conduits being for liquid fuel, means for delivering an atomizing agent to the other of said conduits, means for delivering a combustion-supporting agent to said last-referred-to conduit, the walls of said conduits at their outlet portions being arranged at different points along, and spaced from, said member.

member, and the outlet of the front one of said conduits opening towards said member, whereby the fluid discharging from said first-referred-to conduit discharges towards 5 the side of said member and into the path of the fluid flowing out of the space between the wall of the rear one of said conduits and said member, a casing in which said burner-head is located, said casing containing an 10 outlet, with the burner-head movable in said casing toward and away from said outlet, the space between said outlet and said burner-head constituting a mixing chamber and said head being spaced from said casing whereby 15 a passage through the latter from the atmosphere to said outlet is afforded, and a member located, and slid able, in said casing relative to said burner-head, for controlling the passage of air through said casing to said 20 mixing chamber.

5. A burner comprising a burner-head formed with a tubular member presenting a passage therethrough, means for delivering a 25 combustion-supporting agent to said passage, conduits surrounding said member, one of said conduits being for liquid fuel, means for delivering an atomizing agent to the other of said conduits, means for delivering a combustion-supporting agent to said last-referred-to conduit, the walls of 30 said conduits at their outlet portions being arranged at different points along, and spaced from, said member, and the outlet 35 of the front one of said conduits opening towards said member, whereby the fluid discharging from said first-referred-to conduit discharges towards the side of said member and into the path of the fluid flowing 40 out of the space between the wall of the rear one of said conduits and said member, a casing in which said burner-head is located, said casing containing an outlet, with the burner head movable in said casing toward and away 45 from said outlet, the space between said outlet and said burner-head constituting a mixing 50 chamber and said head being spaced from said casing whereby a passage through the latter from the atmosphere to said outlet is afforded, and a venturi located, and slid able, in said casing relative to said burner head, for controlling the passage of air through said casing to said mixing chamber.

55. A burner formed of a casing containing an outlet, a head in said casing containing passages, the space between said outlet and said head forming a mixing chamber, means for delivering different kinds of fuel through 60 certain of said passages for discharge into said mixing chamber, and means for delivering air through one of said last-referred-to passages, said head being adjustable in said casing toward and away from said outlet and 65 to a degree sufficient to effect substantial

variation in the size of said mixing chamber.

7. A burner formed of a casing containing an outlet, a head in said casing containing passages, the space between said outlet and said head forming a mixing chamber, means 70 for delivering different kinds of fuel through certain of said passages for discharge into said mixing chamber, means for delivering air through one of said last-referred-to passages, said head being spaced from said casing to provide a passage along said head communicating with the atmosphere and with said space, and a venturi adjustable lengthwise of the burner controlling the flow of air through said last-referred-to passage, said head being adjustable in said casing toward and away from said outlet to a degree sufficient to effect substantial variation in the size 80 of said mixing chamber.

8. A burner formed of a casing having an 85 outlet and an inlet in communication with the atmosphere, a fuel-passage-equipped head in said casing, the space between said outlet and said head forming a mixing chamber, said inlet being so disposed that suction 90 is produced therein by the flow of fuel to said outlet, said head being adjustable in said casing toward and away from said outlet and to a degree sufficient to effect substantial variation in the size of said mixing 95 chamber, and a venturi device controlling said inlet and located between said mixing chamber and the point at which the air enters said inlet and adjustable to regulate the flow of air through said inlet.

100 9. A burner formed of a casing having an outlet and an inlet in communication with the atmosphere, a fuel-passage-equipped head in said casing and opening into said chamber, said head being spaced from said 105 casing to provide a passage along said head in communication with said inlet, and a venturi in said passage adjustable toward and away from said head for varying the space therebetween and thereby controlling the 110 flow of air through said passage.

115 10. In a burner, the combination of inner and outer fluid-conducting members one of which surrounds the other thereof, the outlet of the outer one of said members extending lengthwise thereof being very narrow and opening radially, the inner one of said members having a nozzle portion at its outlet shaped to present a venturi portion, the outer end of said nozzle extending beyond the 120 outer one of said members with its forward end tapering outward toward the axes of said members.

125 11. A burner comprising a head formed with an inner tubular member, means for delivering gaseous fuel to said member, means for supplying a combustion supporting agent to the inner member, separate chambers surrounding the inner tubular member one of said chambers serving for a 130

different fuel, means for supplying an atomizing agent to the other chamber, means for delivering a combustion supporting agent to this last mentioned chamber, and means for 5 confining the flow from such chambers in separate narrow areas immediately adjacent each other and the inner tube in concentric relation to such tube.

12. In multiple purpose burners, a hollow 10 inner tube, means comprising separate casing walls for forming a restricted passageway parallel to said tube, said casing walls curving directly toward the tube approximately at right angles and having an annular opening between them so as to direct a narrow unobstructed flow across the path of 15 the flow surrounding the tube and immediately adjacent the latter, the tube terminating beyond the annular opening whereby the flow 20 through such opening and the passageway having approximately equal areas is subsequently combined with flow issuing from the inner tube.

13. In a multipurpose fuel burner, an outer 25 casing having a restricted outlet therefrom and an inlet thereto, an inner tube, a reduced diameter separate casing supported by the tube said casing having an outer and an inner wall, both walls curving directly to- 30 ward the tube and forming a narrow unobstructed concentric opening between them and between them and the tube immediately adjacent each other, the areas of both being approximately the same so that flow from 35 between the walls will be delivered approximately at right angles against the inner tube, and across the flow surrounding the tube, both flows being directed toward the restricted outlet of the outer casing, and means for 40 moving the reduced diameter casing within the outer casing to and fro as desired, whereby different kinds of fuels may be utilized simultaneously or interchangeably in the burner.

45 14. A fuel burner comprising a casing having an outer and an inner wall, both walls curving directly toward and terminating approximately at right angles to the axis of the casing to form a narrow annular opening 50 between the ends of the walls, a central tube forming a support for the casing and projecting past the annular opening, said tube being of reduced diameter adjacent the annular opening to form a narrow passage way past the ends of the walls, the area of such 55 passage way and the annular opening being proportioned to have approximately the same area.

FRANK J. WERNER.
